OIL BURNER

Everett E. Dehart, Omaha, Nebr.

Application April 20, 1931, Serial No. 531,438

3 Claims. (Cl. 158—91)

The principal object of my invention is to provide an oil burner that will not form undesirable carbon inside its retort on either heating flame or pilot flame.

5 A further object of this invention is to provide an oil burner that successfully furnishes the correct quantity of air to the amount of fuel oil being used and one that delivers such needed air at desirable strategic locations inside the oil burner retort.

10 A still further object of this device is to provide an oil burner that keeps the fuel oil in a comparatively cool condition until it reaches the oil burner retort, thereby eliminating possible combustion inside the fuel delivery pipe.

15 A still further object of my invention is to provide an oil burner that will more successfully break up and commingle the fuel oil with air inside the retort.

20 A still further object of this invention is to provide an oil burner that is economical in manufacture and durable in use.

These and other objects will be apparent to those skilled in the art.

25 My invention consists in the construction, arrangement and combination of the various parts of the device, whereby the objects contemplated are attained as hereinafter more fully set forth, pointed out in my claims and illustrated in the accompanying drawings, in which:

Fig. 1 is a side sectional view of my invention mounted and ready for use.

Fig. 2 is a rear view of the hinged gate inside the discharge end of the fan housing.

35 Fig. 3 is a top plan view of this gate taken on line 3—3 of Fig. 2 and more fully illustrates its construction.

Fig. 4 is an enlarged side sectional view of the combination air and fuel delivery pipes.

40 Fig. 5 is an enlarged view of the discharge ends of the combination air and fuel pipes.

Fig. 6 is a top plan sectional view of the oil burner retort showing the entrance therein of the auxiliary air delivery pipe and oil delivery pipe.

45 One of the biggest problems experienced in the use of oil burners using retorts is the forming of carbon inside the retort, which eventually renders the oil burner unserviceable. This is especially true if the oil burner is of the automatic type which automatically returns to a pilot flame after a predetermined temperature has been realized.

When the burner is on pilot flame, very little, if any, circulation of air exists in the retort and

without air carbon rapidly forms inside the retort, eventually putting out the pilot flame and extinguishing the oil burner. I have overcome this by making an oil burner which furnishes sufficient air inside the retort both on heating flame and pilot flame.

I have used the numeral 10 to designate the side wall or door of a furnace. The retort of the invention is generally designated by the numeral 11 and is secured on the inner side of the member 10 and inside the combustion chamber of the furnace or like by suitable means such as bolts. This retort has a detachable lid which I have designated by the numeral 12. A space exists between the forward upper marginal edge of the

retort proper and the forward end portion of the lid 12 and it is through this opening that the flame from the retort is designed to protrude. The numeral 13 designates a comparatively large hollow projection integrally formed on the rear

end of the retort 11 and designed to extend through the member 10. This hollow projection 13 communicates at one of its ends with the inside rear top of the retort 11, and its other end

communicates with the discharge end portion of the centrifugal fan housing 14, as shown in Fig. 1. Rotatably mounted inside the fan housing 14

is a centrifugal fan 15 operatively connected to the armature shaft 16 of an electric motor 17, shown in dotted lines in Fig. 1. The numeral 18

designates an intake pipe having one end terminating adjacent the member 10 and its other end communicating with the inlet port of the fan housing 14. By this arrangement when the fan 15 is rotating, it will obtain its air in a warmed

condition from adjacent the surface of the member 10.

From the fan housing 14 the air will normally be injected through the member 13 into the retort where it will strike the downwardly extending

baffle 19. This will cause the air to move to the bottom of the retort 11 where it will pick up the fuel gases and then pass out through the forward end of the oil burner in the form of a flame. The gasification of the fuel oil inside the retort

and its mixture with the air is made possible by the fact that the retort is inside the furnace and in a hot condition for changing the fuel oil into gaseous form. The numeral 20 designates a horizontal air pipe having its forward end threaded into the rear end of the retort 11 and terminating

near the inside bottom of that member, as shown in Figures 1 and 6. The numeral 21 designates a pipe connection threaded onto the rear end of the pipe 20. Besides its two open ends

this connection has a hollow projection 22 on its top side and which is in communication with the inside of the connection to which it is a part. This hollow projection portion 22 extends upwardly and rearwardly and has threaded into it the pipe 23. As the fan housing 14 is positioned above the member 21, the pipe 23 eventually enters and terminates inside the fan housing 14 adjacent the fan 15, as shown in Fig. 1. To more successfully obtain air from the fan 15, the upper marginal side edge of the pipe 23 extends a considerable distance above the floor of the fan housing 14, thereby promoting a quantity of air from the fan 15 to enter the pipe 23, pass into the member 21, through the pipe 20, and into the retort at a point near the inside bottom of the same. The numeral 24 designates a nut threaded into the rear end of the connection 21. In the center of this nut is a bore 25 which holds and supports the forwardly extending fuel oil pipe 26. This pipe 26 has an outside diameter much smaller than the inside diameter of the member 21 and pipe 20, thereby providing a space between the pipe 26 and the members in which it is located.

As will be noted from Fig. 4, the pipe 26 has its forward end flared and extending slightly beyond the forward end of the pipe 20. The numeral 27 designates a pipe having one end communicating with the inside of the bore 25 and its other end designed to lead to a source of fuel oil not shown. The numeral 28 designates a collar secured in the forward end of the pipe 20 and extending to a point in the same plane with the forward end of the pipe 26. Integrally formed on the forward marginal edge of this collar 28 are a plurality of curved projections 29. By the use of these projections 29, the air passing from the end of the pipe 20 will be given an irregular whirling motion, causing it to more thoroughly mix with the fuel oil emerging from the forward end of the pipe 26.

The numeral 30 designates a baffle gate hinged at its top and positioned in the discharge end portion of the fan housing 14. In this gate is a vertical slot 31. The numeral 32 designates a weight on the rear side of the gate 30 and adjacent the slot 31. This weight carries a bolt 33 which extends through the slot 31 and has the usual manually operated nut 34. By this arrangement, the weight 32 is adjustably secured at various elevations on the gate 30. To prevent undesirable dislocation of the weight 32, I have provided vertical ridges 35 on the gate 30 and at each side of the weight, as shown in Fig. 3.

By the use of this gate 30, the discharge end of the fan will be yieldingly maintained in a closed condition, thereby forcing a goodly part of the air cast off by centrifugal force from the fan 15 to enter the pipe 23. Naturally, the necessary force of the blast of air to open the gate 30 will depend upon the position of the weight 32. If the weight is close to the hinge portion of the gate, very little energy will be required to move the gate to an open position, while on the other hand, if the weight 32 is near the bottom of the slot 31, a great force will be required to move it to an open position.

When the oil burner is operating on pilot flame, the small flame will be in and projecting from the forward end of the pipe 26. Although when on pilot flame the fan 15 will not be rotating, nevertheless sufficient air may pass by natural circulation through the member 18 into the fan housing, thence into the pipe 23 and member 21 and through the pipe 20, which terminates in

close proximity to the pipe 26. This air circulation will be sufficient to furnish desirable quantities of air to the pilot flame and to prevent carbon being formed on the nozzle end of the pipe 26 or inside the retort by the pilot flame. As is well known, when conditions require the operation of the burner on full flame, this pilot flame is used to ignite the oil burner when the motor 17 is started and the supply of fuel oil is automatically increased by conventional and well known control means (not illustrated) so that the device will operate on heating flame. Due to the flared shape of the forward end of the pipe 26 a portion of the pilot flame will be inside this portion where it will be protected from being extinguished by the first air blast from the fan 15. Due to the gate 30, the first rush of this air from the fan 15 will pass into the retort 11 by way of the pipe 23 and as this particular air will be injected longitudinally with and around the pipe 26, its tendency will be to draw the pilot flame outwardly with the oncoming charge of fuel oil and successfully ignite the burner without extinguishing the pilot flame as distinguished from air that would be injected in the upper portion of the retort and permitted to whip downwardly onto the as yet delicate pilot flame. As the air from the fan 15 increases and the fuel oil flow increases proportionately the flame will eventually develop into a heating flame projecting from the forward end of the retort and with such intensity that it cannot be extinguished by the blast of air from the centrifugal fan when the pressure in the fan housing is sufficient to open the gate valve 30 and permit the greater portion of the air blast to pass into the retort through the connection 13.

Although after the fan 15 has reached its maximum revolutions per minute, and the greater volume of air placed in circulation by the fan 15 will pass through the member 13, a sufficient amount of air will always flow through the pipe 20 to prevent any carbon forming in the inside bottom portion of the retort when the oil burner is on heating flame. As we have seen, the amount of air under pressure forced into the pipe 23 will depend upon the adjustment of the weight 32 on the gate valve 30 and the desired amount will depend upon the installation and requirements of the oil burner. This air that passes through the pipe 20 while the burner is on heating flame will prevent the undesirable heating of the pipe 26 and will, as we have seen, by striking the members 29 assume a whirling motion. This vortex created inside the retort will cause the fuel oil to more successfully mix and gasify with the air. As is well known, when the oil burner has produced a predetermined temperature, well known automatic and thermostatic mechanism will stop the motor 17 and reduce the flow of fuel oil through the pipe 27. This fuel oil is reduced to such an extent in its flow through the pipe 27 that only a sufficient amount reaches the forward end of the pipe 26 to furnish the pilot flame. As the force of the air on the gate valve 30 reduces, the gate will accordingly move to a lowered position for yieldingly enclosing the discharge end of the housing 14.

The flared portion of the end of the pipe 26 will not only protect the pilot flame therein and therefrom, but when the motor again starts, the air passing forwardly at each side of the pipe 26 will be guided forwardly and outwardly by the flared end of that pipe and away from

serious contact with the delicate pilot flame until it has reached such proportions that will not be affected by this current of air. This nozzleing of the air and fuel oil is adjustably had by the 5 longitudinal movement of the pipe 20 relative to the pipe 26, and is accomplished by rotating the pipe 20 in the member 21. When the desired location of the end of the pipe 20 is had relative to the forward end of the pipe 26, the pipe 10 should be locked in position by the lock nut 36. The nut 37 also locks the pipe 20 to the retort and member 10.

Some changes may be made in the construction and arrangement of my improved oil burner 15 without departing from the real spirit and purpose of my invention, and it is my intention to cover by my claims any modified forms of structure or use of mechanical equivalents which may be reasonably included within their scope.

20 I claim:

1. In a device of the class described, a retort, a fan housing communicating with the inside top of said retort, a fan in said housing, a means for rotating said fan, a pipe having one of its ends terminating inside and in close proximity to the bottom of said retort and its other end in operative communication with the inside of said fan housing, a second pipe extending inside said first mentioned pipe having one end terminating inside said retort and its other end designed to be in communication with a source of fuel oil, a normally closed yieldable valve in the discharge end portion of said fan housing positioned to direct air from said housing through said first mentioned pipe when said fan is started into operation and operable to open in proportion to the increase of pressure in said housing to permit a relatively greater amount of air to pass from said housing into said retort when said fan is rotating at a comparatively high speed.

25 2. In a device of the class described, a retort, 100 a fan housing communicating with the inside top of said retort, a fan in said housing, means for rotating said fan, a pipe having one of its ends terminating inside said retort and its other end designed to be in communication with a source of fuel oil, a normally closed yieldable valve in the discharge end portion of said fan housing normally substantially closing said discharge and 105 operable to be opened by the pressure of air within the housing upon the operation of said fan, a pipe having one of its ends terminating inside said retort and its other end in operative communication with the inside of said fan housing between said fan and said valve and a second pipe extending inside said first mentioned pipe having one end terminating inside said retort and its other end designed to be in communication with a source of fuel oil.
